UNITED STATES PATENT OFFICE.

INGENUIN HECHENBLEIKNER, OF CHARLOTTE, NORTH CAROLINA, ASSIGNOR TO
CHEMICAL CONSTRUCTION COMPANY, OF CHARLOTTE, NORTH CAROLINA, A
CORPORATION OF NORTH CAROLINA.

COOLING AND OXIDATION APPARATUS.

1,311,395.

Specification of Letters Patent. Patented July 29, 1919.

Original application filed October 17, 1918, Serial No. 258,626. Divided and this application filed April 7, 1919. Serial No. 287,983.

To all whom it may concern:

Be it known that I, INGENUIN HECHENBLEIKNER, a citizen of the United States, residing at Charlotte, in the county of Mecklenburg and State of North Carolina, have invented certain new and useful Improvements in Cooling and Oxidation Apparatus, of which the following is a specification.

In the manufacture of nitric acid, particularly from gases containing nitrogen oxids resulting from the treatment of air by the electric arc or nitrogen oxids obtained from other sources it is necessary or desirable that the gases be cooled to reduce their temperature and also oxidized to convert the nitric oxid (NO) to nitrogen peroxid (NO₂).

The object of the present invention is to provide an improved apparatus for cooling and oxidizing these or other gases in nitric acid processes; but the invention is not limited to this use, since the apparatus may be utilized wherever it may be found suitable.

The cooling of large bodies of gases incident to the processes referred to is a matter of considerable difficulty, and the present apparatus has been designed to provide a rapid and efficient means for the desired purpose. It embodies in one of its forms an elongated chamber or passage through which the gases flow and depending into this chamber are a multiplicity of what I call cooler tubes through which water is caused to flow so that the gases in passing through the conduit flow around or between the tubes, thereby exposing a large surface for the heat exchange action. Each tube contains within the same a filler or inner section which displaces most of the capacity of the tube and causes the water to flow in a film or relatively thin sheet in contact with the inner surface of the wall of the tube. The tubes are of the spur type, that is, they are closed at the lower end, water being supplied through a central pipe to the bottom of the tube and rising as it is heated to the top where it overflows into troughs.

In connection with the cooling chambers equipped with the tubes referred to, I also provide oxidation chambers where oxidation is effected after the first cooling, and then a final cooling chamber for reducing the increase of temperature incident to the oxidiz-

ing action. Means are also provided for collecting such condensate as is formed in the chamber.

In the accompanying drawings, Figure 1 is a plan view of the plant or apparatus, the water supply system of piping being omitted for the sake of clearness. Fig. 2 is a longitudinal section on the line 2—2 of Fig. 1, through one of the cooling chambers, the water supply pipes being included. Fig. 3 is a section on the line 3—3 of Fig. 1. Fig. 4 is a section on the line 4—4 of the same. Fig. 5 is a longitudinal section of one of the cooler tubes.

In the embodiment shown, the apparatus comprises a masonry structure having a series of horizontal chambers disposed side by side, the flow of gases being back and forth through the successive chambers from an inlet at one end to an outlet at the other end leading to an absorption tower, not shown. The first cooling chamber is indicated at 1, the second at 2, the first oxidation chamber at O¹ the second at O² and the third or final cooling chamber at 3. These chambers have the general form of arched masonry passages or tunnels preferably made of acid-proof masonry with a layer of tile 4 at the bottom, draining toward one end of the chambers to an acid drain 5 leading to a pipe 6 for carrying off the condensate. This structure is strengthened or tied together by cross tie rods 7 and longitudinal tie rods 8 connecting outer metal beams 9 at the ends and sides of the structure.

I is the inlet pipe to the first chamber and E is the outlet pipe for the cooled gases. The chambers are separated by longitudinal partitions 10 through which are openings 11, 12, 13 and 14 connecting the chambers in series. The flow of gases is from the inlet I through the chamber 1, thence through the opening 11 to the chamber 2 and so on back and forth to the outlet. Each of the cooling chambers 1, 2 and 3 is provided with a multiplicity of depending cooler tubes C which extend through openings in the roof or top of the chambers. These tubes may be made of any suitable material. Those in the chambers 1 and 2 are preferably acid-proof iron, because of the high temperatures. Those in the chambers 3 may be stoneware. A tube is shown

in detail in Fig. 5. It comprises an outer or spur tube 20, closed at the bottom and open at the top. Within this outer tube is a metal drum or filler consisting of a cylinder 21 closed at the top and bottom, and provided at its lower end with a projecting foot 22 which rests upon the bottom of the outer tube and supports the filler therein. The filler is also spaced from the outer tube 5 by spacers 23 thereby forming an annular space of small area through which the water flows upwardly in contact with the inner surface of the outer tube. Water is supplied to the bottom of each tube by a central pipe 10 24 which extends lengthwise through the drum, and this pipe has a funnel 25 at the top by which it is supplied from any suitable water supply. This supply conveniently consists of a system of piping indicated in Fig. 2 and comprising a main 26 with branches 27 leading to the respective tubes. Obviously any convenient system of water supply may be used. It is to be noted, however, there is a separate water supply to 15 each tube and a separate overflow from each tube and the water does not pass through one tube after passing through another.

The water from the cooler tubes overflows at lips 20^a into a plurality of longitudinal 20 troughs 28 which are mounted upon the top of the chambers and drain to a cross-trough 29 at the end which discharges the waste. The troughs 28 may be made of aluminum and they extend beside the upper ends of the 25 cooler tubes which are arranged in parallel rows throughout practically the whole length and breadth of the cooling chambers, each conveniently resting upon a block or piece of brick 30 on the floor of the chambers.

40 The gases to be cooled are conducted back and forth through the chambers as above described and in passing through the cooling chambers they flow between or in contact with the depending cooler tubes in the cooling chambers, these cooler tubes being sup-

plied with a flow of water in the manner indicated. After a reduction of temperature in the cooling chambers 1 and 2, the gases pass through the oxidation chambers O¹ and O² where they are oxidized by the 50 entrained air or by the air admitted through openings in the ends of the chambers if necessary. The oxidation is attended with some rise in temperature which is again reduced by the passage of the gases through the final cooling chamber 3. The cooler tubes are capable of being individually placed or removed through the holes in the top of the chambers. 31 indicates windows for observation in the ends of the chambers. 60 The cooler tubes are particularly advantageous with respect to the exposure of a large surface for heat exchange and the use of a comparatively small amount of water because of the film arrangement, and also 65 with respect to the convenience of inserting and removing the same without disconnecting or taking down masonry constructions.

This application is a division of my pending application No. 258626 filed Oct. 17, 1918 in which the cooler tubes referred to are claimed.

I claim:

A cooling and oxidation apparatus for gases, comprising a series of horizontal cooling and oxidation chambers located side by side and communicating with each other, means for collecting the condensate in the chambers, water-cooled tubes depending into the cooling chambers, through the roofs 75 thereof, and overflow troughs extending along above the said roofs and arranged to receive the overflow from the tubes.

In testimony whereof, I affix my signature in presence of two witnesses.

INGENUIN HECHENBLEIKNER.
